OIL BURNER

Charles T. Denker and John R. Moore,
Chicago, Ill.

Application October 23, 1948, Serial No. 56,162

5 Claims. (Cl. 158—4)

1

This application relates to burners and, more particularly, liquid-fuel burners such as, for example, oil burners.

Burners of the general nature to which this invention relates have heretofore been known in the art but have had inherent disadvantages such as, for example, not being efficient in operation; not producing efficient and intimate mixing of the fuel with the combustion supporting air; not effecting complete combustion of the fuel, and the like.

A primary object of our invention is to overcome these disadvantages and to provide a burner wherein the fuel and combustion supporting air are intimately mixed in a novel and expeditious manner to insure efficient combustion of the fuel.

Another object of our invention is to afford a burner wherein primary air and secondary air may be fed into intimate contact with the fuel from a common source in a novel and expeditious manner.

An ancillary object is to so construct a novel burner in a manner whereby the amount of primary and secondary air flowing from a common source into contact with the fuel to be burned may be controlled individually.

Yet another object of our invention is to afford a novel burner wherein the fuel and combustion supporting air are caused to swirl in a turbulent manner in the furnace, or the like, in which the burner is used so as to insure intimate mixture of the air and the fuel, and to insure efficient burning of the fuel.

A further object of our invention is to afford a burner wherein the primary and secondary air are introduced into a furnace, or the like, in opposite directions in a novel and expeditious manner.

Other and further objects of the present invention will be apparent from the following description and claims and are illustrated in the accompanying drawings which, by way of illustration, show a preferred embodiment and the principles thereof and what we now consider to be the best mode in which we have contemplated applying those principles. Other embodiments of the invention embodying the same or equivalent principles may be used and structural changes may be made as desired by those skilled in the art without departing from the present invention and the purview of the appended claims.

In the drawings:

Fig. 1 is a side elevational view of a burner embodying the principles of our invention, certain parts thereof being shown in section;

2

Fig. 2 is a detail plan view taken substantially along the line 2—2 in Fig. 1;

Fig. 3 is a detail sectional view taken substantially along the line 3—3 in Fig. 1; and

Fig. 4 is a detail sectional view taken substantially along the line 4—4 in Fig. 1.

The device shown in the accompanying drawings to illustrate a preferred embodiment of our invention comprises a liquid-fuel burner 10, shown mounted in the firebox 12 of a furnace 14, the furnace 14 having a back wall 16 and a front wall 17 extending upwardly from a bottom wall 18.

The burner 10 includes an elongated blast tube 21 which may extend horizontally through the lower end portion of the front wall 17 of the furnace 14, Fig. 1, and is preferably supported in spaced relation to the bottom wall 18 by suitable means such as spacers 22 projecting upwardly from the bottom wall 18. A partition wall 24 extends longitudinally through the tube 21 to thereby divide the tube into two parts, one part comprising an air duct 26 for feeding air to the burner, and the other part comprising a housing 27 within which various parts of the burner may be disposed, as will be presently described in greater detail.

A nozzle 30 is connected by a T-fitting 31 to a feed line 33 mounted in and extending longitudinally through the housing 27. The nozzle 30 extends upwardly from the feed line 33 through a tightly fitting opening 35 formed in the partition wall 24 and projects upwardly through an enlarged opening 37 formed in the top wall of the air duct 26. The discharge orifice 39 of the nozzle 30 is disposed in the upper end portion thereof in a manner whereby liquid-fuel such as, for example, oil, may be fed from a source, not shown, through the feed line 33 into the nozzle 30 and discharged vertically upwardly therefrom into the central portion of the firebox 12.

An air line 41, which may be made of any suitable material such as, for example, a section of pipe, is mounted in the opening 37 around the nozzle 30, in spaced relation thereto, and affords a passageway through which air may be fed from the air duct 26 upwardly past the nozzle 30 to be mixed with the fuel discharged from the orifice 39, as will be discussed in greater detail herein-after.

A swirler mechanism 42, Fig. 2, is mounted in the air line 41 for imparting a rotary motion to the air issuing upwardly from the air line. The swirler mechanism comprises a plurality of vanes 43 mounted on and projecting radially outwardly

from the upper end portion of the nozzle 30, below the orifice 39, the vanes 43 being disposed at an acute angle to the horizontal to thereby cause the air passing upwardly through the air line 41 to be deflected into a rotary motion. As is best seen in Fig. 1, the air line 41 projects a short distance above the upper end portion of the nozzle 30, and has an inwardly projecting, tapered shoulder 45 formed in the upper edge portion thereof, which is effective to cause the air issuing from the air line 41 to be directed against the stream of fuel issuing from the nozzle 30, during an operation of our device.

In addition to the primary air supply line 41, a secondary supply line 47, comprising an inverted substantially U-shaped member having two vertical legs or pipes 49 and 50 interconnected by an intermediate leg or pipe 51, is mounted on the blast tube 21 with the leg 50 extending through and connected to the top wall of the air duct 26 by suitable means such as a nipple 53, and with the other vertical leg 49 disposed above and in vertical alignment with the air line 41. It will be noted that the vertical leg 49 is somewhat shorter than the leg 50 so that the lower end portion of the leg 49 is disposed a substantial distance above the upper end portion of the air line 41 and the nozzle 30.

A distributor member 55 comprising a deflector plate 57 and a deflector head 58 is mounted on the leg 49 of the air line 41 in spaced relation to the walls of the firebox 12 and comprises effective means for intimately mixing the air issuing from the primary line 41 and the secondary air line 47, and the fuel issuing from the nozzle 30, during an operation of our device, as will be discussed in greater detail presently.

The deflector plate 57 may be made of any suitable material such as, for example, fire-clay or fire-brick, and is preferably of a circular shape having an opening 60 formed in the center thereof through which the leg 49 of the air line 41 extends.

The deflector head 58 is hemi-spherical in shape, having a convex outer surface 65 and a concave inner surface 66. A narrow web 68 having an opening 69 formed in the central portion thereof, Fig. 4, extends across the open end of the deflector head 58 and is held in engagement with the lower end portion of the leg 49 of the air line 41 and with the central portion of the deflector plate 57 by a bolt 71 extending upwardly through the hollow shell of the deflector head 58 and through the opening 69 in the web 68 into threaded engagement with suitable means, such as, two lugs 73 and 75 projecting inwardly toward each other from the lower end portion of the leg 49, Fig. 3, and having threads formed on their opposed faces.

The lower face of the deflector plate 57, Fig. 1, has an annular concave surface 78 formed therein, which is disposed circumferentially around the opening 60. The deflector head 58 is so constituted and arranged that air discharged downwardly from the leg 49 of the air line 41 is deflected by the concave surface 66 upwardly against the concave annular surface 78 at an acute angle to the horizontal, and fuel and air discharged upwardly from the nozzle 30 and the air line 41 are deflected outwardly by the convex outer surface 65 into engagement with the concave annular surface 78, also at an acute angle to the horizontal. Hence, it will be seen that, as the fuel and air issue from the nozzle 30 and the pipe 41, the air is caused to rotate around

the stream of fuel by the deflector vanes 43 and is caused to impinge against the stream of fuel by the shoulders 45 formed in the upper edge portion of the pipe 41, so that mixing of the primary air and the fuel is initiated during the original movement thereof from the air line 41 and the nozzle 30. Following this initial mixing of the primary air and fuel, it will be seen that the primary air and fuel are caused to impinge against the lower convex surface 55 of the deflector plate 57 which is effective to cause further atomization of the fuel, further mixture of the fuel with the primary air, and impart a swirling motion to fuel, the swirling layer of primary air impinging substantially directly against, and imparting rotary motion to, the stream of fuel which has been separated into a thin layer by the lower end portion of the deflector head 58. As previously stated, it will be seen that this mixture of fuel and primary air is deflected upwardly and outwardly by the deflector head 58 against the annular concave surface 78 of the deflector plate 57. However, it will be seen that with secondary air being discharged from the air line 47 and deflected upwardly by the deflector head 58 against the concave annular surface 78, the mixture of the fuel and primary air is caused to impinge against the layer of secondary air flowing over the annular concave surface 78 and obviously will be effective to impart a swirling motion to the latter.

The concave annular surface 78 is so constituted and arranged that the mixture of primary air, secondary air, and fuel is caused to be deflected downwardly toward the bottom end portion of the firebox 12, so that the mixture is caused to swirl downwardly in the firebox toward the bottom wall 18 and the lower end portions of the side walls of the furnace 14 and then, upon striking the bottom wall 18 thereof, is caused to be deflected upwardly in the firebox. Thus, it will be seen that a turbulent flow of the air-fuel mixture is caused with our novel device, which is obviously effective to cause an intimate mixture of the fuel and air which is essential to good and efficient combustion of the fuel, the mixture being caused to swirl downwardly toward the bottom of the firebox 12 and then to billow upwardly again in a turbulent manner.

Air may be fed to the primary air line 41 and the secondary air line 47 through the air duct 26 from any suitable common source, such as the blower B, shown mounted on the outer end portion of the blast tube 21. Any one of several different types of blowers, which are well known in the art, may be used.

To afford individual controls for the flow of air through the primary air line 41 and the secondary air line 47, we have mounted a butterfly valve 81 eccentrically mounted on a pivot pin 82 within the air duct 26, between the air line 41 and the air line 47, and another butterfly valve 84 pivotally mounted on a pin 85 within the air duct 26 adjacent to the lower end portion of the leg 50 of the air line 47. Control rods 87 and 88 extend longitudinally through the air duct 26 and are connected at their inner end portions to the valves 81 and 84 by pins 91 and 92, the outer end portions of the rods 87 and 88 projecting outwardly from the end portion of the air duct 26, Fig. 1, to afford handles whereby the control rods 87 and 88 may be moved longitudinally within the air duct 26 to thereby effect pivotal movement of the valves 81 and 84 on the pins 82

and 85, respectively. Thus, it will be seen that by movement of the control rods 87 and 88 in a longitudinal direction, the valves 81 and 84 may be moved between the open positions shown in solid lines in Fig. 1, and the closed positions shown in the broken lines in Fig. 1, the valve 81 being operable to control the effective opening of the air duct 26 between the air line 41 and the air line 47, and the valve 84 being effective to control the effective opening of the connection between the air duct 26 and the air line 47.

It will be seen that the valves 81 and 84, while being operable independently to open and close the entrances into the air lines 41 and 47, respectively, are also operable conjointly to control the flow of air into the air lines 41 and 47, that is, variation in the control position of one of the valves 81 and 84 affects the flow of air past the other of the valves when the latter is in an open position. For example, it will be seen that with the valves 81 and 84 disposed in the positions shown in solid lines in Fig. 1, if one of the valves, such as, for example, the valve 84 is moved toward closed position and it is desired to maintain the same flow of air past the valve 81, the valve 81 should be moved somewhat toward closed position because of the increased flow of air to the valve 81 occasioned by the partial closing of the valve 84. Thus, it will be seen that the valves 81 and 84 cooperate to afford overall control of the flow of air into the burner 10, and also afford independent means for controlling the flow of air into the air lines 41 and 47.

Two electrodes 94 and 95, Figs. 1 and 2, are mounted in the primary air line 41 and project upwardly through two oppositely disposed vanes 43 of the swirler mechanism 42. The electrodes 94 and 95 are disposed in spaced relation above the orifice 39 of the nozzle 38 and afford an effective sparking device, whereby electricity may be fed from a suitable source, not shown, to the electrodes 94 and 95 through wires 97 and 98 which extend outwardly through the housing 27 of the blast tube 21, to thereby afford a device for igniting the burner 10 by remote control.

From the foregoing it will be seen that we have afforded a novel burner which is effective, in a novel and expeditious manner, to impart an efficient turbulent swirling motion to the air-fuel mixture produced by the burner, to thereby insure efficient mixing of the air and fuel and efficient combustion of the latter.

Also, it will be seen that we have afforded a novel burner wherein the parts thereof are constituted and arranged in a novel and expeditious manner, and which is practical and efficient in operation and may be economically produced commercially.

Thus, while we have illustrated and described the preferred embodiment of our invention, it is to be understood that this is capable of variation and modification and we therefore do not wish to be limited to the precise details set forth, but desire to avail ourselves of such changes and alterations as fall within the purview of the following claims.

We claim:

1. In a liquid-fuel burner, a combustion plate having a downwardly facing concave annular surface, an air line extending vertically through the central portion of said plate and having an outlet for feeding air downwardly therethrough, a deflector member having a diameter just slightly greater than the diameter of said central portion mounted below said air line and having an

upwardly facing concave surface located below said outlet for deflecting air discharged therefrom upwardly at an acute angle against the inner marginal edge portion of said concave annular surface, said deflector member having a lower outer convex surface and means for feeding a mixture of fuel and air upwardly around the convex surface of said deflector member and into engagement with said annular surface, said means comprising an upwardly opening air line disposed below said deflector member in position to feed a stream of air upwardly against the convex surface of said deflector member, and a fuel nozzle mounted in said last mentioned air line for feeding liquid fuel into the said stream of air.

2. In a liquid-fuel burner, a horizontally disposed combustion plate having a downwardly facing annular concave surface, an air line extending vertically through said plate in the center of said annular surface and having a downwardly directed outlet portion, means comprising a hemi-spherically shaped deflector member mounted on the lower end portion of said outlet portion of said air line for supporting said combustion plate thereon and having a downwardly facing convex outer surface, said deflector member being hollow and having an upwardly facing concave inner surface disposed below said outlet portion of said air line in axial alignment therewith and with the center of said annular surface for deflecting air discharged from said air line upwardly at an acute angle against the radial inner edge portion of said annular surface, whereby said upwardly deflected air is deflected outwardly and then downwardly past said deflector member by the annular concave surface of said combustion plate and means for feeding a mixture of fuel and air upwardly past said deflector member into engagement with the radial inner edge portion of said annular surface, said means comprising a second air line having an upwardly directed outlet disposed below said outlet portion of said first mentioned air line in axial alignment therewith for feeding a stream of air upwardly against the center portion of said convex surface of said deflector member, and a fuel nozzle mounted in said second air line for feeding liquid fuel into the central portion of said stream of air.

3. In a liquid-fuel burner, a horizontally disposed plate, a nozzle disposed below said plate and directed upwardly in vertical alignment therewith for feeding a stream of fuel upwardly against said plate, an air line having an outlet portion extending upwardly around said nozzle in spaced relation thereto for feeding a stream of air upwardly therewith into engagement with the said stream of fuel, a second elongated air line having an outlet portion mounted above said first mentioned air line in axial alignment therewith and projecting through said plate for feeding a stream of air downwardly toward the said first mentioned stream of air and said stream of fuel, a deflector mounted between said outlet portions of said air lines in alignment therewith, said deflector being disposed below said plate and having surfaces thereon disposed toward said outlet portions of said air lines for directing said air streams in said stream of fuel toward said plate, an elongated air duct extending transversely to said air lines and connected thereto for feeding air thereinto from a common source, and valve means mounted in said duct for controlling the flow of air therethrough into said air lines, said

valve means comprising a valve member mounted in said duct between said air lines and operable to adjust the effective opening of said duct between said air lines, and a valve member mounted in said duct adjacent the connection of said duct and said second air line, and operable to adjust the effective opening of the connection between said second air line and said duct.

4. In a furnace of the type comprising walls defining a firebox, a liquid-fuel nozzle disposed in the lower portion of said firebox and projecting upwardly away from the central portion of the bottom wall of said firebox for directing a stream of fuel upwardly in said firebox, an air line having an outlet portion mounted around said nozzle for feeding a stream of air upwardly therewith and around said stream of fuel, a second air line mounted in said firebox and extending above the outlet portion of said first mentioned air line and said nozzle and having an outlet directed downwardly toward said first mentioned air line and said nozzle for feeding a stream of air theretoward, and means for mixing said air streams and said fuel stream and directing said mixed streams downwardly and outwardly toward the bottom of said firebox, said means comprising a horizontally disposed plate mounted on said second air line above said outlet portion of said first mentioned air line and said nozzle in spaced relation to said walls, said plate having an annular concave lower surface surrounding said second air line, and a deflector having a convex lower surface and a concave upper surface mounted between said outlet portion and said outlet in axial alignment with said annular surface for deflecting said air streams and said stream of fuel outwardly against said annular surface at an acute angle to the horizontal.

5. In a liquid-fuel burner, a horizontally disposed plate having a concave annular lower surface, an air line mounted in said plate and having an outlet for feeding a stream of air down-

wardly away from the center of said annular surface, a deflector member mounted below the outlet of said air line for directing said air stream upwardly against said annular surface at an acute angle to the horizontal, said deflector member having a convex lower surface and being disposed vertically below said center of said annular surface with the outer edge portion thereof disposed horizontally inwardly of the outer edge portion of said annular surface, and means for feeding a mixture of liquid-fuel and air into engagement with said annular surface and said stream of air, said means comprising a nozzle mounted below said deflector and directed theretoward for feeding a stream of liquid-fuel therewith, an air line having an upwardly directed outlet portion mounted around said nozzle in spaced relation thereto for feeding a stream of air upwardly therewith, and a plurality of deflector vanes extending between said nozzle and said outlet portion of said last mentioned air line at an angle to the horizontal for deflecting said last mentioned air stream around said stream of fuel in a circular motion.
